(57) CLAIM

The ornamental design for a box with a corner sticker, as shown and described.

DESCRIPTION

FIG. 1 is an elevational view of a box with a corner sticker showing my new design; and,

FIG. 2 is a reduced scale, environmental view thereof. The characteristic feature of the design resides in the cut outs which create a figure reminiscent of an angel.

The broken lines showing a box and 3 stickers is for illustrative purposes only and form no part of the claimed design.
